UNITED STATES PATENT OFFICE.

ROBERT PAPENDELL, OF DETROIT, MICHIGAN.

OIL-BURNER.

1,384,085.

Specification of Letters Patent. Patented July 12, 1921.

Application filed January 31, 1920. Serial No. 355,525.

To all whom it may concern:

Be it known that I, ROBERT PAPENDELL, a citizen of the United States, residing at Detroit, county of Wayne, State of Michigan, have invented a certain new and useful Improvement in Oil-Burners, and declare the following to be a full, clear, and exact description of the same, such as will enable others skilled in the art to which it pertains to make and use the same, reference being had to the accompanying drawings, which form a part of this specification.

This invention relates to apparatus for burning oil, and has for its object an improved organization of parts adapted to so act upon a quantity of relatively heavy oil as to raise its temperature before ignition to a high point, as well as break it up into relatively small particles, which, mixing with the steam or hot air which has already served to heat it, projects these particles in a fine spray from a nozzle located adjacent the point where the combustion is to take place.

In the drawings:

Figure 1 is a side elevational view of my assembled device.

Fig. 2 is an enlarged sectional elevation of the central portion of the device, where the oil is first acted upon by the steam.

Fig. 3 is a sectional plan, taken along the line 3-3 of Fig. 2.

Fig. 4 is a side sectional view taken from the same position as Fig. 1.

Fig. 5 is a cross-sectional view, along the line 5-5 of Fig. 4.

A represents the shell or casing, within which is contained the oil chamber B, adapted to be fed, as through the passage C. The walls D of the lower part of this oil chamber are surrounded by the steam or hot air space E, into which steam or hot air flows from a suitable generating source through the valve-controlled passage F. The steam chamber E may be cleansed and accumulation of sediment removed therefrom through the bottom vent G, and sediment may be removed from the oil chamber by opening the bottom passage C'.

It will be noted that the relatively small top portion of the oil chamber B communicates with the largest one of the three concentrically arranged discharge or spraying nozzles J, K and L, whereas the middle nozzle K, extending one step farther back

through the wall H, is in communication with a steam chamber M, into which, when the control valve N is open, steam can flow through the passage-way P from the valve-controlled cruciform passage R, common to both the steam chamber M and the chamber D already described.

Extending even farther back in the casing than the wall H is the rearward end of the smallest nozzle L, into which steam may flow when the controlling valve T is open. Each of these spraying nozzles being thus connected with an individually regulatable source of pressure, whether steam or hot air, and the first named and largest one J being also connected with a source of oil supply, there are provided plural sources of steam to mingle with the steam and oil particles which are coaxially delivered thereabout from the forward end of the largest tube or nozzle J. Considerable mingling of steam and oil particles, sufficient in fact for some purposes, thus results from the action of the steam admitted to the oil chamber by opening of the control valve F. When, however, finer breaking up of the oil particles, and a higher projective velocity of the mixture is desired, one or both of the smaller nozzles K and L is brought into action by the opening of the respective controlling valves N and T. There is thus projected through the center of the mixture, at the forward or discharge end of the large nozzle J, one or two (as the case may be) additional steam columns from the shorter nozzles K and L, which serves to further break up the oil particles already in suspension in the steam and more or less thoroughly mingled therewith.

The extent of these nozzles forwardly to variant distances from the shell or casing, A, properly spaced from one another if desired, by the spider A', is shown particularly in Figs. 1 and 4. The outer end of the longest and largest nozzle J is capped by a centrally perforated spray regulator V, which is carried on the ends of the flanking and diametrically located slide rods U, the rear end of each of which passes slidably through the guide bearing X on the outer shell Y. The other two tubes K and L, which are of smaller diameter than the nozzle J and contained therewithin, are also shorter, so that the steam particles emerging from them pass through and mingle with

the mixture from the nozzle J, and with it are controlled as to their escape from its end by this regulator V.

A saddle Z is keyed to each of these slide bars, and from each saddle there extends rearwardly a link Z' which is connected with a pivoted regulating lever Q, the lower end of which straddles the notched quadrant edge Q', so that the spring-held latch Q² in 5 10 15 20 25 30 35 40 45 50 55 60 65 70 75 80 85 90 95 100 105 110 115 120 125 130

the handle Q frictionally engages it to hold the handle, and consequently its connected parts leading to and including the terminal V, which are held in desired position relatively to the projecting shell Y.

15 The operation of this device is as follows: Being adapted to work upon heavy oils, and to deliver the same in finely broken up or dispersed shape at the point where combustion is to take place, it is desirable that 20 the temperature of the oil as furnished to the oil chamber B, with which is connected the largest one, J, of the spraying nozzles, be quickly and consistently raised to a high degree, and to this end the steam chamber D 25 is made to surround it, thus maintaining a body of live steam or hot air all about the lateral walls B. The steam or hot air is thus projected at a high velocity through the upper portion of the chamber and across 30 the top surface of the oil that has risen thereinto, and in its rush forward to escape through the large nozzle J, not only picks up the top surface of the oil, but, as it carries it forward, breaks the highly heated 35 oil into fine particles which lend themselves readily to combustion, especially when supplemented by the action of one or both of the smaller nozzles K and L, when the point of intended ignition is reached, this point 40 being just outside of the adjustable and centrally perforated terminal plate V. The exact distance from this plate, may, however, easily vary to such a degree that, under some circumstances, the longitudinal projection of 45 the mingled steam and oil particles straight out from the end of the nozzle will give the best results. In such case, the handle Q is moved rearwardly (to the left as shown in Fig. 1), so as to force the guide rods U for- 50 ward, and thus move the centrally perforated plate V appreciably away from the capped end of the nozzle J. In other cases, however, combustion conditions may render it advisable to have the projection of the 55 mingled steam and oil particles follow more or less oblique lines from the continued central axis of the nozzle, as indicated by the dot and dash lines at the extreme right end of Fig. 4. In this case the handle Q is 60 thrown forwardly (to the dotted line position shown in Fig. 1), thus drawing the slide rods U and their supported plate V closely against the end of the nozzle J, thus reducing to a minimum the proportion of the 65 mingled oil and steam particles which are

projected straight forward, and diverting most of them in the general directions indicated by the dot and dash lines in Fig. 4 above referred to.

A possible variation from the above described construction, wherein steam or hot air alone is used for the breaking up and projection of the oil particles, is indicated at O in Figs. 1 and 4, and consists in the inclusion of a supplemental hot air pipe leading 70 into the projecting shell Y intermediate the ends of the included large spraying nozzle J. By its heating influence thereon it increases the degree of vaporization of the already more or less mingled oil and hot air (or steam) proceeding forwardly therethrough from the shell A.

What I claim is:

1. In combination with a shell provided with a plurality of chambers and apertures 85 regulating means for admitting a supply of oil and of live steam within one of the chambers thereof, an oil heating chamber partially surrounding said chamber, into which both oil and live steam are adapted to 90 be admitted, a plurality of spaced telescoping tubes, one of which is connected with said oil and steam chamber, the others of said tubes being connected with other chambers in said shell from said oil and steam 95 chamber, and means for regulating the admission of oil and steam into the other chambers independently of one another and of said first-named oil and steam chamber.

2. In combination with a plurally chambered and apertured shell, a plurality of discharge tubes spaced in telescoping relation, a plurality of separate oil chambers, each connected with one or the other of said discharge tubes, a supplemental heating 105 chamber partially surrounding that one of the oil chambers with which the largest of said discharge tubes is connected, and regulating means for admitting live steam into each one of said oil chambers to effect the 110 volatilization of the oil contained therein, and its expulsion through the tube leading therefrom.

3. In an oil burning apparatus, the combination with a plurally chambered and 115 apertured shell, of a corresponding number of concentrically arranged discharge nozzles leading therefrom, means for admitting oil and live steam into each of said shell chambers independently of the others, means for additionally heating the oil in that one of the chambers with which the largest dia- 120 metered discharge nozzle is connected, and means adapted to control the possible escape of mingled steam and oil particles from said 125 nozzles, whereby its direction of egress and further volatilization may be regulated.

4. The combination of an oil chamber, a steam chamber arranged thereabout, a plurality of concentrically and spaced discharge 130

nozzles with the largest one of which said oil chamber is connected, a plurality of supplemental oil chambers, each connected with one or the other of the smaller discharge nozzles, means for regulatably admitting a supply of steam into each one of said oil chambers, and an adjustable terminal member for said discharge nozzles whereby the direction and extent of egress of the mingled oil and steam particles proceeding from said nozzles may be regulated.

5. In an apparatus for burning oil, in combination with a plurally apertured and chambered shell, independent regulating means for admitting a supply of oil and of

live steam to each of said chambers, a heating chamber partly surrounding one of said oil and steam chambers, and a discharge tube appurtenant to each of said chambers, said tubes being arranged one within the other and being adapted to discharge their mingled oil and steam at a common point for combustion.

10 In testimony whereof, I sign this specification in the presence of two witnesses.

ROBERT PAPENDELL.
